(57) **CLAIM**

The ornamental design for a bottle, as shown and described.

DESCRIPTION

FIG. 1 is a front perspective view of a bottle showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof, shown with cap removed.

The broken lines are included for the purpose of illustrating the portions of the bottle, namely the interior wall, interior sphere, spray top, bottom surface and cap that form no part of the claimed design.

1 Claim, 5 Drawing Sheets

FIG. 1
